UNITED STATES PATENT OFFICE.

JAMES BUCHNER SPEED, OF NEW YORK, AND ARTHUR H. FALK, OF BROOKLYN, NEW YORK, ASSIGNORS TO WESTERN ELECTRIC COMPANY, INCORPORATED, OF NEW YORK, N. Y., A CORPORATION OF NEW YORK.

TELEPHONE-RECEIVER DIAPHRAGM.

Application filed July 2, 1923. Serial No. 648,884.

To all whom it may concern:

Be it known that we, JAMES B. SPEED and ARTHUR H. FALK, citizens of the United States, residing at New York, in the county 5 of New York, State of New York, and Brooklyn, in the county of Kings, State of New York, respectively, have invented certain new and useful Improvements in Telephone-Receiver Diaphragms, of which the 10 following is a full, clear, concise, and exact description.

This invention relates to methods of stretching diaphragms and its object is to provide an acoustic diaphragm having a 15 high natural period of vibration.

In accordance with the features of this invention a diaphragm to be stretched is fastened near its outer edge to a relatively expandible conical ring, and this ring is 20 stretched uniformly to a slightly larger diameter by forcing into it a second conical ring having an outer diameter slightly larger than the smallest inner diameter of the first ring, and composed preferably of 25 somewhat heavier and less yielding material.

In its application to the manufacture of acoustic apparatus for telephonic or similar purposes utilizing metallic diaphragms, the diaphragm is fastened to the relatively expandible metallic ring by soldering, brazing, welding, or staking and this ring is uniformly 30 stretched to give the desired tension to the diaphragm by forcing into it a second ring, thus stretching the diaphragm radially, and uniformly.

By the use of this invention diaphragms are provided which have not only an unusually high period of natural vibration, but a uniform radial stress throughout by reason of the flow and adjustment of the metal of the diaphragm at its yield point. It makes possible the use of an exceedingly thin diaphragm which may be held taut without making the edge portions thicker 40 than the middle portion and without deforming the edge portion by corrugating or punching. This feature enables the use, if desired, of a stretched diaphragm of very brittle material such as high silicon steel, 45 which will introduce a high electrical resistance for the purpose of diminishing eddy currents. In short, a diaphragm is obtained 50 which is in all respects superior to those diaphragms stretched in the usual manner.

A feature of the invention is the provision of an improved mounting whereby the diaphragm is tensioned and positively held in its adjusted vibrating periods through the provision of a plurality of rings adapted to form with the diaphragm a unitary structure which may be inserted or removed from the instrument with which it is used without changing the adjustment of the diaphragm.

The drawings show one embodiment of 65 the invention. Fig. 1 shows a diaphragm and the apparatus for stretching the same. Fig. 2 shows the apparatus when the diaphragm is stretched. Fig. 3 shows this apparatus embodied in a telephone receiver. 70

A ring 6, preferably conical in shape, has fastened to its smaller end a diaphragm 7, which may be composed of metal or other material. The ring 6, which should be of expandible material, is secured to the diaphragm by any satisfactory method; for example, by soldering, brazing, staking, or welding. A second ring 8 conical in shape, has an outer diameter at its smaller end 75 somewhat greater than the inside diameter 80 of ring 6 where it touches the diaphragm 7. Ring 8 is pressed into ring 6 toward the diaphragm to force ring 6 outwardly in all directions. Ring 6 carries outwardly with it those portions of the diaphragm to which 85 it is attached, thus uniformly stretching the diaphragm. For this purpose a press which exerts an equal pressure on all sides of ring 8 should be used, in order to secure 90 the desirable uniform stress throughout the diaphragm. Ring 8 should preferably be made of heavier or less yielding material than ring 6. For example, ring 6 may be composed of thin, soft iron or steel having 95 a low yield point, and ring 8 may be composed of thicker or harder iron or steel.

When it is desired to solder the diaphragm to the ring 6 in cases where the diaphragm is composed of a metal or alloy which is not easily or strongly solderable, a rim of 100 tin or other metal may be electroplated upon the outer edge of the diaphragm by suitably rotating its rim in an electrolytic bath so as to deposit thereon a thin coating of metal to which the ring may be soldered. 105

While the stretched diaphragm has properties which make it especially desirable for use in acoustic apparatus for telephonic or

like purposes such as the telephone receiver shown in Fig. 3, it may be used for any purpose for which a stretched diaphragm is required.

5. What is claimed is:

1. In combination, a ring, a diaphragm secured to one edge thereof and an expanding member forced into said ring for stretching the diaphragm uniformly and to form with
- 10 the said ring a unitary structure for permanently holding said diaphragm stretched.
2. In combination, a ring, a diaphragm se-

cured to one edge thereof, a second heavier ring having its outside diameter greater than the inside diameter of the first ring and 15 forced into said first ring for stretching the diaphragm uniformly and to form with the first ring a unitary structure for permanently holding said diaphragm stretched.

In witness whereof, we hereunto subscribe 20 our names this 27th day of June A. D., 1923.

JAMES BUCHNER SPEED.
ARTHUR H. FALK.
